UNITED STATES PATENT OFFICE.

HIRAM GEO. McCARTY, FRANK L. FELTES, AND OTTO R. KRIVAN, OF CLEVELAND, OHIO.

CONCEAL OR CACHET FILLER AND SEALER.

Application filed October 3, 1924. Serial No. 741,505.

To all whom it may concern:

Be it known that we, HIRAM G. McCARTY, FRANK L. FELTES, and OTTO R. KRIVAN, citizens of the United States, residing at 5 Cleveland, in the county of Cuyahoga and State of Ohio, have invented certain new and useful Improvements in Conceal or Cachet Fillers and Sealers, of which the following is a specification.

10 This invention relates to improvements in fillers and sealers for cachets or conceal, having for an object the provision of an apparatus in which the conceal may be filled, sealed and then removed therefrom 15 without injury.

Another object is to provide a filler and sealer of this character in which the conceal or cachet carrying plates are removable as a unit whereby to prevent accidental separation of the two concavo-convex wafers which make up the conceal.

It is also an object to provide in an apparatus of this character, means for filling the conceal with medicine or the like in powdered form in such a manner as to prevent lodging of any portions upon the flanges included in the conceal structure.

It is likewise an object to provide a filler and sealer of this character comprising a minimum number of simply constructed parts such as will materially reduce the cost of manufacture and facilitate assembly and operation.

Other objects are in part obvious and in part pointed out hereinafter.

In order that the invention and its mode of operation may be readily understood by persons skilled in the art, we have in the accompanying illustrative drawings, and in the following detailed description based thereon set out one possible embodiment of the same.

Figure 1 is a plan view of the filler and sealer in closed or sealing position;

45 Figure 2 is an end view showing the relative positioning of the bed and cover plates while wafers are being filled;

50 Figure 3 is a plan view of the bed plate showing the spaced longitudinal channels which permit of slidable movement of the supplemental plates when the wafers have been sealed;

55 Figure 4 is a plan view of the bed plate and supplemental plate carried thereby, this supplemental plate being slightly withdrawn;

Figure 5 is a plan view of the funnel supporting plate;

60 Figure 6 is a detail cross sectional view of a portion of the bed plate, showing other parts associated therewith for filling of a wafer;

65 Figure 7 is a detail cross sectional view showing the two-part wafer at the beginning of the sealing operation; and

70 Figure 8 is an edge view of the forward end portion of the two supplemental or wafer carrying plates, wafers being positioned therein.

Having more particular reference to the drawings throughout which similar reference characters designate similar parts this improved conceal or cachet filler may be stated as comprising bed and base plates, each having longitudinally extending channels designed to be relatively aligned and opening through corresponding ends of said plates. A pair of supplemental or cachet supporting plates is slidably connected to adjacent faces of the bed and base plates, 75 and have aligned openings to receive the wafers forming the cachets and being relatively fixed to prevent separation of the wafers after they have been sealed and during the removal of the completed cachets 80 from the apparatus.

75 The bed plate and base plate are identically formed with one exception which will be specified hereinafter, consequently detailed description will be directed to the base 85 plate only. As shown in Figures 2 and 3, this base plate 10 is substantially rectangular in configuration, and is provided in its upper face with an under cut way 11 which is designed to receive a supplemental or 90 cachet supporting plate 12, this plate having beveled longitudinal edges to snugly engage the under cut portions of the way 11. This supplemental plate, as shown in Figure 6, is provided with a set of openings to 95 receive and support parts of the conceal or cachets, it being clear that these parts include flange portions which take over and rest upon the upper face of the supplemental plate. By reference to Figures 1, 4, and 8 100 it will be seen that the supplemental plates are provided with hand pieces 13 at their outer ends and with an inter-engaging socket and pin 14 and 15 respectively 105 whereby to insure against relative shifting 110 of said plates during the filling, sealing and removal of the conceal or cachets.

Formed in the under cut channel 11 and extended longitudinally therein is a pair of spaced grooves or channels 16 which open through one end of the bed plate 10 as shown in Figures 2 and 3. The portion between the spaced grooves or channels 16 is raised to form a rib 17 as illustrated in Figures 2 and 3, thereby forming a central support for the supplemental or cachet supporting plate which is arranged in the aforementioned under cut channel or way 11. The provision of these channels permits slideable removal of the supplementary plates together with the sealed wafers or cachets, it being obvious that any other construction would prohibit such relative sliding of these parts. Legs 18 are integrally formed about the periphery of the base plate whereby to elevate the intermediate portions from a table or the like support.

At longitudinally aligned corners, bosses 19 are formed, each boss carrying a tapered pin 20 which is designed to be snugly fitted into a similarly shaped socket 21 formed in enlarged portions of the cover plate 22. This cover plate as shown, includes an under cut way 23 to receive a slideable supplemental plate 24 and is further provided with spaced channels or grooves 25 as in the case of the bed plate. Legs 26 are also integrally formed with the cover plate as shown in Figure 2. Portions of both the bed and base plates are cut away as shown in the several figures in order to reduce the quantity of material used as well as the weight of the structure.

As has been previously stated, the cachets or conceals each consist of two concavo-convex wafers made up of soluble material and including annular radial flanges. In filling these conceals one half or one of the wafers is arranged in each of the openings 27 formed in the supplemental plate 12, the flanges of the wafers being rested upon the upper face of the plate 12 associated with the bed plate. The body of each lower wafer projects through the opening in the supplemental plate and is spaced from the bottom of the adjacent channel or groove formed in the bed plate as shown in Figures 6 and 7. When the entire set of wafers has been positioned as shown in Figures 2 and 6, we arrange thereon a funnel supporting plate 28 which as shown in Figures 5 and 6 consists of a comparatively heavy metal plate having openings 29, alinable with the openings 27 in the supplemental plate 12. As is obvious, the positioning of this funnel supporting plate as shown, prevents displacement of the wafers during the filling operation, said plate being held in fixed relative position through the provision of apertured ears 30 which fit over the standing pins 20 carried by the bed plate 10.

During the filling operation a funnel 31

as shown in Figures 2 and 6 may be removably set into the several openings thereby assuring movement of the powdered medicine or the like directly into the wafers. With completion of the filling process, the funnel and its supporting plate are removed. The cover plate carrying the top sections or wafers which complete the conceal structure is positioned over the bed plate, with the result that covers are formed for the first wafers which received the powdered medicine. It is understood that the flange portions of the wafers carried by the cover plate have been moistened prior to their being positioned over the wafers carried by the bed plate. With positioning of the bed and cover plates as shown in Figure 7, a slight pressure upon the cover plate will result in adhesion of the flange portions of the two wafers. At this stage the two supplemental plates as shown in Figures 1 and 8 being inter-connected, may be slid longitudinally with respect to the bed and cover plates bringing with them through one end of the channels the completed conceals or catchets. The provision of a structure which permits slideable removal of the catchet supporting plates insures against injury of the conceals or catchets as is often experienced in use of other types of filler. As shown in Figures 1 and 4 these supplemental plates are provided with hand pieces or grips whereby to facilitate the aforementioned simultaneous sliding movement.

It is understood that the wafer supporting plates may be formed with different sized openings therein so as to permit use of the apparatus in filling and sealing variousized catchets or conceals.

Minor changes in the details of construction may be made within the scope of the appended claims and such changes we consider within the spirit of our invention.

We claim:

1. An apparatus of the character described comprising a pair of separable plates having opposed longitudinal channels opening through corresponding ends thereof, said plates being arranged to align the channels, supplemental plates slidably carried by said separable plates, said supplemental plates having a set of openings communicating with the channels and adapted to support concavo-convex wafers and means whereby the supplemental plates may be slideably removed from said separable plates.

2. An apparatus of the character described comprising a bed plate, a cover plate arrangeable upon the bed plate, said plates having opposed under-cut ways, channels formed in the bottoms of said ways, supplemental plates longitudinally slideable in said under-cut ways and having openings communicating with said channels, and

means whereby said supplemental plates may be connected for simultaneous withdrawal from the bed and cover plates.

3. An apparatus of the character described comprising a bed plate, a cover plate arrangeable upon the bed plate, said plates having relatively alined opposed longitudinally extending channels formed in the bottoms of said ways, a pair of supplemental plates arranged in said ways and slideable longitudinally therein, and said supplemental plates having a set of openings communicating with the channels, and adapted to support concavo-convex wafers for filling and sealing.

4. An apparatus of the character described comprising a bed plate, a cover plate arrangeable upon the bed plate, each plate having an under cut way in its inner face opening through one end thereof, said plates each having a pair of transversely spaced longitudinally extending channels opening

through the same end with said under cut way, and a pair of supplemental plates slideably disposed in said under cut ways and removable therefrom through one end, said supplemental plates having openings communicating with the channels to receive and support concavo-convex wafers.

5. An apparatus of the character described comprising a bed plate, a cover plate arrangeable upon the bed plate, said plates having a pair of alinable opposed ways opening through corresponding edges thereof, and supplemental plates separably connected and arranged in the ways, said supplemental plates having a set of relatively alined openings.

In testimony whereof, we affix our signatures.

HIRAM GEO. McCARTY.
